Primary Examiner — Cynthia Ramirez

(74) *Attorney, Agent, or Firm* — Kutak Rock LLP; Bryan P. Stanley

(57) **CLAIM**

The ornamental design for an overhead creeper, as shown and described.

DESCRIPTION

FIG. 1 is a front left side perspective view of an overhead creeper showing my new design.

FIG. 2 is a top plan view of the overhead creeper of FIG. 1.

FIG. 3 is a left side elevation view of the overhead creeper of FIG. 1.

FIG. 4 is a right side elevation view of the overhead creeper of FIG. 1.

FIG. 5 is a bottom plan view of the overhead creeper of FIG. 1.

FIG. 6 is a rear elevation view of the overhead creeper of FIG. 1; and,

FIG. 7 is a front elevation view of the overhead creeper of FIG. 1.

The broken lines are to show portions of the overhead creeper which form no part of the claimed design.

1 Claim, 7 Drawing Sheets
